UNITED STATES PATENT OFFICE.

HARRY AUSTIN AND LA VIRGNE J. KIMBALL, OF SAN FRANCISCO, CAL.

PROCESS OF PHOTOGRAPH-COLORING.

SPECIFICATION forming part of Letters Patent No. 257,811, dated May 9, 1882.

Application filed January 4, 1882. (No specimens.)

To all whom it may concern:

Be it known that we, HARRY AUSTIN and LA VIRGNE J. KIMBALL, of San Francisco, in the county of San Francisco and State of California, have invented certain new and useful Improvements in the Process of Photograph-Coloring; and we do hereby declare that the following is a full, clear, and exact description thereof.

10 This invention relates to the art of portraiture and picture-making generally; and our object is to so treat a photographic picture of any object that the effect will be quite natural and life-like of the object taken in color, as 15 well as in shades and shadows, as a good oil-painting; also, to combine with the picture a background which will set off the picture in bold relief, as will be hereinafter explained.

We are aware that paper on which photographs have been taken has been rendered semi-transparent by saturating the paper with Canada balsam, paraffine, and other substances, and that such photographs have been cemented on glass and painted on the backs 25 with colors. Such process we do not claim as our invention.

The following are the steps necessary to produce a picture by our process, together with the compounds which we use: We take a photograph of an object, or a fully-retouched albumen print of any size, and paste the paper on which the picture is taken on plate-glass with a cement which is composed of the following ingredients, mixed together in about 30 the proportions specified for each: amyrum, six drams; distilled water, six ounces; nitrate of strontia, six grains; granulated sugar, one ounce; gum-arabic, one-quarter of an ounce. We press out all surplus cement, preferably 35 by means of a rubber roller, and after the paper is fully dry we remove as much of the paper fiber as possible by means of emery-paper, pumice-stone, or other suitable means, care being taken not to injure the film of chemicals 40 constituting the print or picture adhering to the glass plate. This operation leaves on the glass a transparent picture of the object taken in the camera, to intensify the transparency of which and give it solidity and smoothness 45 of effect, as well as to protect the delicate film from the injurious effects of the atmos-

phere, the plate of glass to which it is attached is plunged into a bath composed of equal parts of paraffine and white beeswax, rendered fluid by heat, and all superfluity of wax removed while hot by a cloth or other suitable means. When the plate is cold we color the back of the picture with oil-colors, and deepen the shades and tints by applying the colors in such manner as to give beauty 55 and life to the picture, which effect can be produced by any person having ordinary artistic skill in the use of colors. When this is dry we add a second glass or backing, which we prefer should be very thin, and we secure this 60 backing to the picture-plate by cementing strips of paper to the edges of the two plates. Upon the back of this second plate we paint the complexion, drapery, &c., if the picture be a human figure, care being taken to accurately 65 and sharply preserve all of the outlines of the figure. When this touching is finished and dry a third plate of glass, strip of wood, cardboard, or other substance is added to the back of the second plate, so as to leave a space between the two plates, previous to which, however, this backing is painted or otherwise prepared to represent the background of the picture. This plate or board may be covered with a frosting composed of the following ingredients: Epsom salts, two ounces; distilled water, six ounces; gum-arabic, one dram. This compound will give a very fine effect to the picture, as well as a natural depth to the background. Instead of this frosting, a very pretty 70 effect may be produced by substituting colored fabrics—such, for instance, as silk or velvet—properly arranged and stretched over the face of the backing.

Having thus fully described our invention, 75 what we claim, and desire to secure by Letters Patent, is—

1. The process of producing colored pictures from photographs, the same consisting of the following steps: first, in fixing the paper on which is the picture to a plate of glass by means of a cement composed of amyrum, water, nitrate of strontia, granulated sugar, and gum-arabic; second, removing almost all of the paper fiber by abrasion, leaving only a thin 80 film adhering to the glass; third, coating this film with a hot solution of paraffine and bees-

wax; fourth, coloring the back of the picture; fifth, excluding air from the same by cementing another transparent plate to the back of the first and retouching in colors on the back 5 of this plate; and, sixth, applying a third plate or board set back of the second plate and frosted or covered with colored fabric, all substantially as described.

2. In the process of treating photographic 10 pictures to be applied on glass and rendered transparent, the compound consisting of amy-

lum, water, nitrate of strontia, granulated sugar, and gum-arabic mixed together in about the proportions specified.

In testimony that we claim the foregoing as 15 our own we affix our signatures in presence of two witnesses.

HARRY AUSTIN.

LA VIRGNE JOHN KIMBALL.

Witnesses:

JOHN E. HAMILL,

JAMES SMILEY.
